VEHICLE DOOR LOCK CONSTRUCTION

George M. Nyquist, Detroit, Mich., assignor to
 Divco-Twin Truck Company, Detroit, Mich., a
 corporation of Michigan

Application July 21, 1939, Serial No. 285,782

12 Claims.

(CL 70—211)

The present invention relates to vehicle door lock constructions and more particularly to lock constructions for vehicle doors such as doors for delivery vehicles, which are comparatively thin, although it is not limited to this use.

Although satisfactory locks have been heretofore proposed for comparatively thick vehicle doors, such as are employed on pleasure vehicles, they require a long hub portion of comparatively large diameter, which makes it impractical to incorporate them in the comparatively thin doors of delivery vehicles and the like, with the result that the doors of this class of vehicle are usually not provided with locks at all or else are provided with complicated expensive lock constructions which have not proven altogether satisfactory.

It is accordingly the major object of this invention to provide novel lock constructions for thin vehicle doors, which are highly efficient and yet simple and rugged in design.

A further important object is to provide a lock mechanism operable exteriorly of the vehicle door for directly contacting the inside door lever and locking it against unlatching movement.

Another object is to provide an inertia-controlled locking device for automatically locking the inside door lever against movement when the door is closed with a predetermined force.

A further object is to provide a door with a 30 sliding plunger and a spring for locking the inside door handle against operation, and to so design the parts that the spring functions both to directly engage the door lever and to return the plunger to unlocked position.

Another object is to provide the inside door lever of a vehicle with means for selectively engaging it and locking it against unlatching movement and to so design the door lever that it may be manually manipulated from the inside of the 40 vehicle to render the locking means ineffective.

Further objects will become apparent as the specification proceeds in connection with the annexed drawings, and from the appended claims:

In the drawings:

Figure 1 is a fragmental side elevational view of a vehicle embodying the door locking device of my invention;

Figure 2 is a top plan diagrammatic view of the door construction shown in Figure 1, showing 50 the door sections in partially opened position;

Figure 3 is a fragmental elevational view taken from the inside of the vehicle looking in the right-hand side door, with the parts in locked position;

Figure 4 is a sectional view taken along the line 4—4 of Figure 3, and shows one of the latches for holding the door in closed position;

Figure 5 is a sectional view taken along the line 5—5 of Figure 3, looking in the direction of the arrows;

Figure 6 is a sectional view taken along the line 6—6 of Figures 3 and 5, illustrating the parts as they appear when viewed in the direction of the arrows, the position of door 11 when in closed position being indicated by phantom lines;

Figure 7 is a fragmental sectional view showing the inside door lever, and is taken substantially along the line 7—7 of Figure 3, looking in the direction of the arrows;

Figure 8 is a sectional view of the lock plunger mechanism, and is taken substantially along the line 8—8 of Figure 3;

Figure 9 is a sectional view through the lock mechanism and is taken substantially along the line 9—9 of Figures 3 and 10; and

Figure 10 is a sectional view through the lock mechanism taken along the line 10—10 of Figure 3.

With continued reference to the drawings, wherein like reference characters have been employed to designate like parts throughout the several views thereof, and with particular reference to Figure 1, I have illustrated my invention as being applied to the door of a delivery vehicle A, having a door opening 10. Hinged to the rear edge of the door opening is a folding door section 11, and hinged to its free edge is a second folding door section 12.

As seen in Figure 2, when the door is unlocked, the door sections hinge upon each other and swing together about the rear edge of the door opening as an axis, and when they are in fully open position they lie parallel to each other against the side of the vehicle, with door section 12 outermost.

From door section 12 is provided at its top and bottom with a latch mechanism, but as they are identical in construction only the upper one will be described. Referring to Figure 4, mounted for sliding movement in a bracket 13 secured inside door 12 is a bracket 14, in which a latch bar 15 is mounted for sliding vertical movement. Secured to the upper end of rod 15 by means of a set screw 16 is a latch 17, and it is also mounted for sliding movement in a bracket 18. A coil compression spring 19 acting against bracket 14 constantly urges the latch and latch bar upwardly toward latching position.

Latch 17 cooperates with a keeper plate 21

which is secured to a bracket 22 by means of a pair of screws 23 and nuts 24. Bracket 22 has secured thereto a resilient striker strip of rubber or the like 25 for cushioning door closing shocks and a rail 26 which constitutes the upper framing of the body and supports a roof 27. A plate 28 extending outwardly from member 26 carries a guide rail 29 for the door, but as this forms no part of the present invention and is not claimed herein, it will not be further described.

The lower and upper portions of door 12 are accordingly securely locked against opening movement when latches 17 are disposed behind their keepers 21, and by moving the latches upwardly and downwardly respectively against the action of compression springs 19, the door may be unlatched and opened.

Latch rods 15 each extend into a latch bar operating mechanism casing C. Referring to Figure 5, casing C comprises a front plate 32 having flanged edges 33, and a cover plate 34. The parts are held in assembled relation to each other and to door 12 by means of a plurality of bolts 35 and nuts 36. Upper rod 15 is secured to a C-shaped member or yoke 38 and lower rod 15 is secured to a somewhat similarly shaped member 39.

Members 38 and 39 are actuated by means of a cam member 42 as seen in Figure 6, which is mounted for rocking movement in plates 32 and 34. Yoke members 38 and 39 embrace a cylindrical portion 41 provided on member 42. Member 42 is provided with a pair of cams 43, which, as seen in Figure 5, cooperate with the horizontal portions of yoke members 38 and 39 to lift the lower latch member and depress the upper latch member when member 42 is rocked. Member 42 is actuated by means of a handle or outside door lever 45, which is journaled in a plate 46, and the latter is secured to the door and plate 32 by means of a pair of screws 47. Door handle 45 is square in cross-section and is provided with a hollow internally threaded stem 48, for a purpose which will now be described.

An inside door lever 49 is provided with a square opening 51 and permanently secured therein, as by peening, is a sleeve member 52, which is square in section. Sleeve 52 and extension 48 of handle 45, which is also square in section, extend into a square opening 53 in member 42, and are secured rigidly together in end-to-end relationship by means of a screw 54, which extends through sleeve 52 and is threaded into member 48.

The inside and outside door levers are accordingly rigidly secured together and to cam member 42, so that upon actuation of either of them, so as to rock the cam in a clockwise direction (Figure 3) will operate the latches and unlock the door.

As seen in Figures 5 and 6, door 11 is provided with an inner member 55 for reenforcing it and its front edge is doubled back upon itself at 56 and welded to a hinge member 57. Door 12 is also provided with an inner reenforcing member 58 and its rear edge is doubled back upon itself at 59 and welded to an angle member having a curved surface 61, which extends over into contact with door 11 when the doors are in closed position so as to hide the hinged joint therebetween. Member 61 is in turn welded to a hinge member 62 which is connected to hinge member 57 by means of a hinge pin 63.

It will be apparent from the disclosure so far made that the doors of delivery vehicles are comparatively thin and that the conventional lock-

ing mechanism which is usually associated with the door handle and latch actuating shaft of pleasure vehicles cannot be used, due to the fact that it is impossible to journal a shaft of any appreciable length in the door.

I have accordingly provided a novel locking mechanism which is mounted in the door independently of the latch actuating mechanism and is adequately supported to resist the forces to 10 which it is subjected in use. My device is located outside the door but cooperates directly with the inside door lever, and it is located a sufficient distance from the axis of rotation of the lever to make it unnecessary to employ massive parts 15 for holding the latch shaft against rocking movement. In other words, by providing a long lever arm adequate resistance to unlocking torque applied to the outer handle is afforded by a moderate force. This construction will now be described.

The novel locking construction comprises broadly a slidably plunger mounted in the door and operable from the outside with a key or the like, a leaf spring member mounted inside the door and operable to both urge the plunger towards unlocked position and also constituting an abutment which is disposed in the path of movement of the inside door lever when the plunger is disposed in locking position.

Referring to Figures 3 and 7, the inside door lever 49 carries a flat leaf spring-like member 65, which is secured thereto by a pair of rivets 66. Member 65 cooperates directly in abutting relation with the locking means hereinafter described, and it is provided with a reversely curved 35 portion 67 constituting a handle by which it may be manually moved into the dotted line position shown in Figure 7.

Referring to Figure 8, the locking member also comprises a leaf spring-like member 68, which is secured to the inside of door 12 by means of a pair of screws 69. Screws 69 extend through openings in the inside member 58 and are threaded into a reenforcing member 71 located on the inner side thereof. Member 71 is provided 45 with a flange portion 72 for properly spacing member 58 from door 12 proper and for strengthening the structure.

Member 68 is provided with a reversely bent portion 74 which forms an abutment for the inside door lever 49, and a foot portion 75, which engages the locking plunger designated as P.

From the structure so far described it is apparent that with member 68 disposed in the position shown in Figure 8, if outside door handle 45 is grasped and an attempt made to unlatch the door, the inside door lever will strike abutment 74 of member 68 and positively lock the parts against movement. When the plunger P is moved into the dotted line position shown in Figure 8, member 68 will assume the dotted line position and be disposed out of the path of movement of inside door lever 49, with the result that either the inside or the outside door lever may be operated to unlatch the vehicle door. In the event that the operator should enter the vehicle with plunger P in locked position, and close the door, he may grasp extension 67 of member 65 and flex the latter into the dotted line position shown in Figure 7, so that it can be actuated 70 without striking member 68.

The locking plunger construction I preferably use is as follows: An opening 77 is provided in door 12 and a collar 78 is welded between door 12 and member 58 in alignment with opening 77, as shown in Figure 8. A smaller diameter open-

ing 79 is provided in member 58 for a purpose that will presently appear.

A generally cylindrical body member 81 closely fits within opening 77 and collar 78 and is disposed in abutting relation with wall 58. It is preferably secured in place by a plurality of screws 82, which pass through openings in member 58 and are threaded into the body.

Plunger P is slidably mounted within member 81 and is provided with a closed bottom 84. The range of sliding movement of plunger P is determined by a screw 85, which is threaded into the plunger body, carries a pair of lock washers 86 and cooperates in sliding engagement with the wall of a longitudinal recess 87 provided in body member 81. Plunger P may accordingly undergo limited longitudinal movement with respect to the body member but it cannot rotate therein by virtue of screw 85 engaging the walls of slot 87.

Slidably mounted in the plunger is a lock bolt 88 which cooperates with a recess 89 formed in body member 81. Lock bolt 88 is urged towards locking relationship with opening 89 by means of a compression spring 91, which seats against the bottom of a recess 92 formed in the plunger. As will be apparent from the drawings, when lock bolt 88 is disposed in locking cooperation with opening 89, plunger P will be disposed in the locking position shown in Figure 8.

Lock bolt 88 is controlled by a lock barrel 93, which is mounted for limited rocking movement within plunger P, and is retained against removal therefrom by means of a set screw 94, which is threaded into the plunger. The end of lock barrel 93 is formed with an offset projection 95, which cooperates with a notch in lock bolt 88 to retract the latter against the action of spring 91 when the lock barrel is rocked. Lock barrel 93 is normally locked against the rotation within the plunger by any well known tumbler construction, and is unlocked by means of a key 96 in a well known manner. Since the key and tumbler construction is one well known in the art and is not claimed per se, it will not be further described.

Taking up the operation of the lock mechanism, and assuming that the parts are in the position shown in Figure 8, with the door closed, it cannot be opened without the use of key 96, because inside door handle 49 will strike abutment 74 if an attempt is made to open it by rocking handle 45. Upon inserting key 96 into lock barrel 93 and rocking it through a predetermined angle the part 95 thereof will draw lock bolt 88 from opening 89 and allow spring 68 to return plunger P to the dotted line position shown in Figure 8. The door may now be unlatched from either side.

My novel construction also possesses that further advantage that the plunger constitutes an inertia controlled means for automatically locking the door when the latter is "slammed" or closed with a predetermined force. For instance, assuming that the door is open, and plunger P is disposed in the dotted line (unlocked) position shown in Figure 8, if the door is swung closed with sufficient force plunger P has sufficient mass which manifests itself as inertia and moves into the full line (locked) position of Figure 8 against the action of spring 68. Of course, the door may be locked at any other time by merely depressing plunger P into its full line position in Figures 8 and 9 as spring 91 will urge lock bolt 88 into opening 89.

My novel lock mechanism may also be used in

the rear doors of delivery vehicles or in other doors wherein the inside door lever is not normally manually grasped and actuated to unlock the door. It is to be understood that in this construction the inside door lever may be made rigid, since it need not be flexed to release an operator from the interior of the vehicle, but if desired it may be made flexible, like lever 65 of the construction shown in Figure 7, without departing from the spirit of the invention.

Although I have shown my lock mechanism embodied in a double pivoted door assembly, it is to be understood that it may be embodied in a single pivoted door or a sliding door without departing from the spirit of the invention. Also, if it is used with a sliding door and it is desired to secure an automatic inertia control feature, the plunger axis may be located parallel to the travel of the door.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. For use with a door mounted for opening and closing movement with respect to a door opening and having a latch mechanism for holding it in closed position and a shaft projecting from the inside to the outside of said door and being operable to actuate said latch mechanism when it is rocked; an inside door lever and an outside door lever rigidly mounted on said shaft; a barrel mounted for sliding movement in said door adjacent said shaft in a direction substantially parallel thereto; a spring member mounted inside said door and engaging said barrel so as to resiliently urge the latter toward unlocking position; abutment means on said spring member for engaging and restraining said inside lever against unlatching movement when said barrel is in locking position, and means for locking said barrel in locking position.

2. The device defined in claim 1, wherein said inside door lever is provided with a resilient portion cooperating with said spring member, whereby the free end thereof may be manually flexed in a plane normal to said door and withdrawn from locking cooperation with said spring member, so as to unlock the door from the inside.

3. The device defined in claim 1, wherein said spring member comprises a flat leaf spring secured at one end to said door and having its free end directly engaging said barrel.

4. The device defined in claim 1, wherein said spring member comprises a flat cantilever spring secured at one end to said door and having its free end engaging said barrel, said spring being substantially tangentially disposed with respect to the arc of rotation defined by the locking portion of said inside door handle.

5. A lock construction, adapted for use with a door hinged for swinging cooperation with a door opening and having latch mechanism for holding it in closed position; a shaft adapted to be journaled in said door remote from the hinge thereof and operable to actuate said latch mechanism when it is rocked; an inside lever

and an outside lever rigidly mounted on said shaft; and inertia-controlled locking means mounted on said door and embodying a locking member mounted for movement in a direction substantially normal to said door and tending to lie out of the path of movement of said inside lever, said locking means having sufficient inertia to project said locking member into the path of said inside lever when said door is swung toward closed position with a predetermined force. 10

6. In a door lock, a door latch-controlling shaft journalled in a door or the like, an outside lever and an inside lever rigidly mounted on said shaft, a cantilever spring secured at one end to the inside of said door and having an abutment at its free end for locking cooperation with said inside lever, said spring being normally urged out of the path of movement of said inside lever, and locking means, operable from the outside of said door, for projecting said spring into the path of said inside lever, to thereby lock the latter against movement. 15

7. The device defined in claim 6, wherein said inside lever comprises a resiliently yieldable portion cooperating with said spring which may be manually flexed out of locking engagement with said spring to unlock the door from the inside. 20

8. The device defined in claim 6, wherein said locking means comprises a plunger mounted for sliding movement in a direction substantially parallel to said shaft and having means for locking it in projected position. 25

9. The device defined in claim 6, wherein said locking means comprises a plunger slidably mounted in a socket in said door, and said spring is provided with a finger portion extending into said socket in contacting relation to said plunger. 30

10. For use with a door mounted for opening and closing movement with respect to a door frame and having a latch mechanism cooperating with said door frame to lock the door against opening movement and a shaft extending from the outside to the inside of said door for operating said latch mechanism, an inside lever and an outside lever mounted on said shaft for rocking the same, a lock assembly mounted on said door; means mounting a part of said lock assembly for sliding movement in a direction substantially normal to said door, and having a 40

part projectible into the path of rocking movement of said inside lever to lock the same; and means for locking said lock assembly part in projected position, said lock assembly comprising a lock barrel and a spring for urging the same out of projected position, said spring having an abutment face cooperating in contacting relationship to said inside door lever. 45

11. A lock construction adapted for use with a door hinged for swinging cooperation with a door opening and having latch mechanism for holding it in closed position; a shaft adapted to be journalled in said door remote from the hinge thereof and operable to actuate said latch mechanism when it is rocked; an inside lever and an outside lever rigidly mounted on said shaft; and inertia-controlled locking means mounted in said door and automatically projectible into the path of movement of said inside lever when said door is swung into closed position, said locking means comprising a lock barrel mounted for sliding movement and a spring urging said barrel toward unlocking position, said spring having an abutment for engaging said inside lever, and said barrel having sufficient inertia to overcome said spring and project the latter into the path of said inside lever when said door is swung into closed position with a predetermined force. 50

12. For use with a door mounted for opening and closing movements with respect to a door frame and having a mechanism cooperating with said door frame to lock the door against opening movement and a shaft extending from the outside to the inside of said door for operating said latch mechanism, an inside lever and an outside lever mounted on said shaft for rocking the same; a lock assembly mounted on said door; means mounting a part of said lock assembly for sliding movement in a direction substantially normal to said door and having a part projectible into the path of rocking movement of said inside lever to lock the same; and means for locking said lock assembly parts in projected position, said inside lever having a resiliently yieldable portion cooperating with said sliding part of said lock assembly, whereby it may be manually flexed out of locking engagement with said part to unlock the door from the inside. 55

GEORGE M. NYQUIST.
